DESIGN FOR A TOY DOG OR SIMILAR ARTICLE

Edgar Rhodes Hauser, Birmingham, Ala.

Application December 19, 1945, Serial No. 124,841

Term of patent 7 years

(Cl. D34—2)

To all whom it may concern:

Be it known that I, Edgar Rhodes Hauser, a citizen of the United States, residing at Birmingham, in the county of Jefferson and State of Alabama, have invented a new, original, and ornamental Design for a Toy Dog or Similar Article, of which the following is a specification, reference being had to the accompanying drawing, forming part thereof.

I claim:

The ornamental design for a toy dog or similar article, as shown.

EDGAR RHODES HAUSER.
